ATTORNEYS.

UNITED STATES PATENT OFFICE.

GEORGE J. FOX, OF FRANKFORD, PENNSYLVANIA.

PLUNGER SASH-WEIGHT-MOLDING APPARATUS.

Application filed March 3, 1923. Serial No. 622,496.

To all whom it may concern:

Be it known that I, GEORGE J. FOX, a citizen of the United States, residing at Frankford, county of Philadelphia, State of Pennsylvania, have invented a new and useful Plunger Sash-Weight-Molding Apparatus, of which the following is a specification.

My invention relates to a novel construction of a plunger sash weight molding apparatus, wherein I dispense with much expensive and superfluous mechanism and steps heretofore employed, and whereby I am enabled to mold sash weights or other straight castings of various shapes in cross section without jolting or ramming and I also dispense with the necessity of a cope or top for the mold. By my novel method and apparatus an unlimited production can be attained at a low cost by unskilled labor, and there is no handling or reversal of the flask required.

It further consists of a novel manner of forming the eye in the outer end of the sash weight casting by the employment of novel cores, whereby a large number of finished weights without fins or protuberances are produced at each operation of any desired length of unusual smoothness and uniformity.

It further consists of other novel features of construction and advantage all as will be hereinafter set forth and pointed out in the claims.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of the plunger and patterns, stripping plate, and flask of a plunger molding apparatus, embodying my invention.

Figure 2 represents a sectional view of the stripping plate in detached position.

Figure 3 represents a vertical sectional view of the plunger, stripping plate and flask, the patterns being shown in elevation, showing the manner of forming the mold.

Figure 4 represents a vertical sectional view of the mold with the cores in place ready to pour.

Figure 5 represents a plan view of Figure 4.

Figure 6 represents, on an enlarged scale, a sectional view of the upper left-hand portion of Figure 4.

Figure 7 represents, on an enlarged scale, a perspective view of a core in detached position.

Figure 8 represents a perspective view of a finished sash weight produced by my method and apparatus.

Similar numerals of reference indicate corresponding parts.

Referring to the drawings—

1 designates the forming head or plunger composed of the plate or disc 2, from the top of which projects the rod 3, while from the bottom thereof project or depend the patterns 4, which are of the general contour of the sash weights, or other articles to be produced, being in the present instance cylindrical in cross section and provided with tapered or chamfered points or lower terminals 5.

6 designates the forming box or flask and 7 the sand therein. 8 designates the stripping or pattern plate having the holes 9 therein, which is adapted to be placed upon the top of the flask 6, said stripping plate having the central boss 10 projecting from the bottom thereof, from which radiate the radial ribs or forms 11 whose bottom edges converge upwardly and inwardly, so as to produce the radial outwardly inclined gates 12, in the top of the sand, which radiate from the central basin 13, formed by the boss 10 in the top of the sand as seen in Figures 4 and 5, said radial gates at their outer ends communicating with the holes 14 formed in the sand by the descent of the patterns 4. The cores 15 are wedge-shaped, being conical or circular for the major portion of their upper area, as indicated at 16, and have the downwardly converging walls 17 and 18, and the horizontal slot 19 therethrough, whereby their upper outer portion fits nicely in the upper ends of the holes 14, but leave a passage or gate as 20, see Figures 4 and 6, for the metal to flow to the holes 17. It will be understood that the bottom 21 of the flask is perforated, and that suitable clamps as 22 are provided which

2
snap over the pins 23, so as to hold the plate and flask securely together during the operation of forming the mold.

The operation is as follows:

- 5 The flask 6 which may be round, square or other polygonal shape, is filled with sand 7 to its top, and the stripping plate 8 having as many guide holes 9 therein as there are patterns is then clamped on the top of the flask, as seen in Figure 3. The plunger 1 carrying the patterns 4, then descends, being actuated downwardly and upwardly by any suitable means, and pushes the patterns into the sand through the stripping plate to a depth determined by the length of the sash weight required. The plunger is then reversed and the patterns withdrawn, and the pattern plate or stripping plate 8 removed. The cores 15 are then 10 dropped into the tops of the holes 14, whereby the eye 24 in the finished weight 25 is formed, and the mold now appears as seen in Figures 4, 5 and 6 and is ready to pour, the metal flowing from the central basin 13 to the runners or gates 12 to each mold 14. By adjusting the length of the stroke of the plunger 1, sash weights may be made of many lengths off the same patterns, and I further dispense with the 15 cope and no jolting or ramming is required as the displacement of the sand by the forcing of the patterns thereinto, displaces and packs the sand to a consistency compact enough to stand the pressure of the iron dropping from the top of the mold to the bottom thereof.

It is desirable that the lower ends of the patterns which enter the sand be chamfered so that the sand will be displaced and compacted enough to stand the strain of pouring without packing too hard to "take" the iron, said patterns requiring no tapering other than at their chamfered ends.

40 I am aware that a machine has been proposed having a plurality of patterns upon a plate, a flask placed upon the same and filled with sand, the same being jolted or rammed to make it compact and said flask raised and lifted from the patterns. In another process, I am aware that a flask is placed upon a pattern plate holding a plurality of patterns, filled with sand jolted and raised to a desired height and the plunger reversed and withdrawn from the mold 45 through the stripping plate.

50 My process is differentiated from the foregoing since the sand is put into the flask, without any patterns whatsoever in said flask; a stripping plate is then placed upon the open end of said flask, and a plunger forces the pattern into said flask and this process of forcing the patterns into the sand, eliminates all ramming and jolting. The pressure of forcing these patterns into 55 this flask of loose sand, not rammed or

jolted, displaces and packs the sand to a consistency compact enough to stand the pressure of the iron dropping from the top of the mold to the bottom thereof.

There is no handling or inversion of my 70 flask required, as the same is constantly maintained in one position, as seen in Figures 1, 3 and 4. My patterns by any simple mechanical means, which it is not necessary to describe in detail, are forced into 75 the sand as seen in Figure 3, the weight of the patterns, serving to assist in a natural manner in the forming of the molds, and upon the upward withdrawal of the patterns and the removal of the plate 8, the 80 mold appears as seen in Figures 5 and 6 and is ready to pour, no cope being required.

The employment of the cores 15 having the inclined wall 17, which meets the top 85 of the core to form the wall or cut away portion 26, enables me to form a good looking eye 24 at the top of the weight, which is amply reinforced by the top cross bar 27, seen in Figure 8, which is a much 90 better construction than that having the eyes formed of a separate wire cast into the top of the weight, as has heretofore been done.

95 It will be understood that my process and apparatus are adapted to the molding and casting of other devices than sash weights as the patterns may be of polygonal contour instead of cylindrical, in cross section, and for casting other articles than sash weights, the cores may not need to be employed, as is evident.

100 It will now be apparent that I have devised a novel and useful plunger sash weight molding apparatus which embodies 105 the features of advantage enumerated as desirable in the statement of the invention and the above description, and while I have, in the present instance, shown and described 110 a preferred embodiment thereof which will give in practice satisfactory and reliable results, it is to be understood that such embodiment is susceptible of modification in various particulars without departing from the spirit or scope of the invention or sacrificing any of its advantages.

115 Having thus described my invention what I claim as new and desire to secure by Letters Patent, is:—

120 1. The herein described method of casting sash weights, which consists in placing a pattern plate having a plurality of radially disposed apertures and a central boss on the top of the sand in the flask, and forming therefrom in the top of the sand a central basin and radial gates, next forcing a plurality of patterns of solid cross section and arranged in circular form having chamfered ends through the apertures in said plate into 125 said sand, next withdrawing said patterns 130

thereby forming molds open at their end, next removing said plate and next positioning slotted wedge shaped cores in said molds to form the sash weight eyes.

- 5 2. In a device of the character stated, the combination of a flask open at its top and closed at its bottom, a pattern plate having a plurality of radially disposed apertures and arranged in circular form secured to the top
 10 of said flask and having a central bottom boss and radial inclined ridges on its bottom for forming a central basin and radial gates in the top of the sand, a plunger having a plurality of pendant patterns of solid cross
 15 section arranged in circular form, adapted to be moved axially to enter the sand and upwardly when withdrawn from the sand, and wedge shaped slotted cores inserted in the top of the molds formed by said patterns.
 20 3. In a plunger sash weight molding apparatus, a flask open at its top and closed at its bottom, a plate having a plurality of radially disposed apertures arranged in circular form, means for clamping said plate
 25 to the top of said flask, a boss in the bottom of said plate to form a central basin and downwardly and outwardly inclined gates in the sand, and a plunger having a plurality of pendant patterns arranged in circular form movable axially to enter the top of the sand in said flask, to form the molds, the upward movement of said patterns with-
 30 drawing them from the sand, whereby no inversion of said flask is required and a cope
 35 is dispensed with.

4. In a plunger sash weight molding apparatus, a flask open at its top and closed at its bottom, a stripper plate for the top of said flask having a plurality of radially disposed apertures arranged in circular form 40 and having a boss on its bottom for forming in the sand a central basin and radial gates, and a moving plunger carrying a plurality of patterns arranged in circular form having chamfered ends adapted to enter the top of 45 the sand to form the molds, whereby no inversion of said flask is required and a cope is dispensed with.

5. In a plunger sash weight molding apparatus, a flask open at its top and closed at 50 its bottom, a plate having a plurality of radially disposed apertures arranged in circular form, means for clamping said plate to the top of said flask, means on the bottom of said plate to form a central basin and 55 downwardly and outwardly inclined gates in the sand, and a plunger having a plurality of pendant patterns arranged in circular form movable axially to enter the top of the sand in said flask to form the molds, the 60 upward movement of said patterns with-
 65 drawing them from the sand, whereby no inversion of said flask is required, and a cope is dispensed with, in combination with horizontally slotted cores positioned in the upper portions of said molds.

GEORGE J. FOX.
